(57) **CLAIM**

We claim the ornamental design for a food service container, as shown and described.

DESCRIPTION

FIG. 1 is a top perspective view of a food service container showing our new design, in an opened configuration;

FIG. 2 is a front, elevational view thereof;

FIG. 3 is a rear, elevational view thereof;

FIG. 4 is a left side, elevational view thereof, with the right side, elevational view being a mirror image thereof;

FIG. 5 is a top, elevational view thereof;

FIG. 6 is a bottom, elevational view thereof;

FIG. 7 is a top, perspective view of the food service container shown in FIG. 1 in a closed configuration;

FIG. 8 is a front, elevational view thereof;

FIG. 9 is a rear, elevational view thereof;

FIG. 10 is a left side, elevation view thereof, with the right side, elevational view being a mirror image thereof;

FIG. 11 is a top, elevational view thereof; and,

FIG. 12 is a bottom, elevational view thereof.
